UNITED STATES PATENT OFFICE.

WILLIAM M. SCOTT, OF PHILADELPHIA, PENNSYLVANIA.

TIME-LIMIT CIRCUIT-BREAKER.

No. 861,611.

Specification of Letters Patent.

Patented July 30, 1907.

Application filed January 31, 1907. Serial No. 354,991.

To all whom it may concern:

Be it known that I, WILLIAM M. SCOTT, a citizen of the United States, residing at Philadelphia, in the county of Philadelphia and State of Pennsylvania, have invented a new and useful Time-Limit Circuit-Breaker, of which the following is a specification.

My invention relates to electrical switches, circuit breakers, or the like, having applied to the tripping or control mechanism thereof a start delaying device of the character shown and described in Letters Patent of the United States No. 830,537, September 11, 1906.

It is the object of my invention to provide a start delaying device which shall be uniform in action irrespective of the number of times it is called into action 15 or the interval of time between responses.

It is the further object of my invention to render the start delaying device adjustable to the end that it may respond with varying degrees of promptness to applied forces of the same or different magnitudes.

20 My invention resides also in other features herein-after described and pointed out in the claims.

For an illustration of one form my invention may take reference is to be had to the accompanying drawing, in which:

25 Figure 1 is a side elevation of an automatic circuit breaker having applied thereto my start delaying device. Fig. 2 is a vertical sectional view showing the start delaying device and associated parts. Fig. 3 is a front elevation, partly in section, of a portion of the 30 tripping mechanism. Fig. 4 is a top plan view of the cup of the start delaying device. Fig. 5 is a bottom plan view of the movable sucker element. Fig. 6 is a front elevational view of a part of the adjusting means for the tripping mechanism.

35 Referring to Fig. 1, 1 and 2 are, respectively, the upper and lower main stationary contact blocks secured upon the base or switchboard 3, such as marble or any other suitable insulating material. The laminated bridging member 4, adapted to engage and bridge the 40 terminal blocks 1 and 2, is supported on but insulated from the arm 5 which is pivoted at 6 in the bracket or housing 7 secured upon the base 3.

45 Supported by and in electrical communication with the upper terminal block 1, is the stationary shunt metallic contact 8 with which coöperates the movable shunt metallic contact 9, supported by springs 10 upon the arm 5, though insulated therefrom. A bracket 11, secured upon and in electrical communication with the terminal block 1 supports the stationary shunt carbon 50 contact 12, pivoted at 13. The coöperating movable shunt carbon 14 is pivoted at 15 in the member 16 secured to but insulated from the arm 5. The operator's handle 17 is pivoted to the bracket 7 at 18 and extends inwardly beyond the pivot 18 and is pivoted at 19 to the 55 toggle link 20, which, in turn, is pivoted to the arm 5

at 21. The link 20 and the extension 22 of the handle 17 form a toggle, serving, in the well known manner, to cramp the laminated bridging member 4 into engagement with the contact blocks 1 and 2.

The roller 23 is pivoted at 24 in the operator's handle 17, and is adapted to be engaged and held by the latch 25, pivoted at 26 to the housing 7 and having the lip 25'; a spring 27 serves to press in an upward direction against the latch 25 whose counterclockwise rotation about the pivot 26 is limited by a suitable stop. The latch actuating member 28 is also pivoted at 26 and carries at its forward end the adjustable screw 29, which serves to strike upon the top of the latch 25 to disengage it from the roller 23. The tail 30 of the latch actuating member 28 is in the path of travel of the striking member 31, which forms an integral part of the armature carrying frame 32, pivoted to the base or housing at 33. An armature 34 is secured to the frame 32 and is adapted to be attracted by the poles 35 of the magnet whose coil 36 is connected at one end to the terminal 37 and at the other end to the lower portion 2' of the terminal block 2. The armature frame 32 has two downwardly extending arms 38 between which is pivoted the member 39 tapped at its center 40 to receive the vertically extending rod 41 upon the lower end of which is supported the movable sucker element 47 of the start delaying device. The rod 41 has at its lower end a transversely extending integral portion 42 which bears pivotally at its ends 43 upon the pin or rod 44 extending diametrically through the ring 45. The ring 45 is, in turn, pivoted at opposite ends of a diameter (at right angles to the rod 44) in ears 46 at the ends of a diameter and on the upper side of the movable sucker member 47. By this construction the sucker member 47 has an universal joint or gimbals connection with the vertical rod 41, allowing it to adapt itself perfectly to the relatively stationary sucker member 48 formed in the bottom of the cup 49. The quadrants 48 are surfaced and rise above the depressions 50 in the bottom of the cup 49, and operate as the stationary sucker surfaces. With these coöperate correspondingly raised sucker quadrants 51 on the relatively movable sucker element 47, the intervening quadrants 52 being depressed and having relatively 100 large apertures 53 therein. A boss 54, midway between the quadrants 51, extends upwardly from the surface 52 and is faced off in the same plane with the quadrants 51.

The vertically extending rod 41 extends through 105 a central opening in the cover 55 screw threaded upon the cup member 49. Embraced between the cover 55 and the flange on the cup 49 and free to move with respect thereto is the circular stirrup member 56 having projecting studs 57 engaging loosely in the 110

vertical slots 58 in the members 59 secured to and extending vertically down from the housing 7. The stirrup member 56 is supported by vertically extending portions 60 pivoted at their upper ends at 61 to 5 the arms 62 which are pivoted concentrically with but independently of the armature frame 32 at 33. The ends of the arms 62 remote from pivots 33 are joined by the plate 63 to which is secured plate 63' having the angularly disposed slot 64. The surface 10 of the plate 63' is curved in an arc whose center is at 33. Upon the front of the housing and at its lower portion is secured the plate 65 having the horizontal slot 66 through which extends the end of the screw 67 engaging in the block 68 having the projecting pin 15 69 which engages loosely in the slot 64 of the plate 63'. The block 68 has projections which engage in the slot 66 serving as a guide, so that moving the screw 67 backward and forward horizontally will shift the plate 63', in an arc about the center 33 and, therefore, 20 lift or lower the stirrup 56 which carries the cup 49 of the sucker device. This adjustment, therefore, really causes an adjustment of the distance between the armature 34 and the poles 35, so that the circuit breaker will respond to different current loads, 25 such loads being indicated on the plate 65 by the scale 70 with which co-operates the pointer 71 moving with the block 68 and screw 67. The scale 70 is obtained by calibration test in the usual manner. When it is desired to set the circuit breaker to respond to a 30 desired value, the screw 67 is moved to the right or left until the pointer 71 comes opposite to that current value inscribed on the scale 70. The armature 34 is then at a proper distance from the poles 35. The operator then tightens the screw 67, thus clamping 35 the block 68 to the plate 65 and holding the parts in the desired adjusted position.

The operation is as follows: With the parts in position as shown in Fig. 1, the circuit closing position, when the current in the circuit reaches or exceeds the value 40 corresponding with the indication of the pointer 71 on the scale 70, the armature is attracted by the poles 35 due to the magnetism generated therein by the current flowing through the coil 36. The armature is unable to respond immediately, however, due to the sucker action 45 of the quadrants 51 which bear upon the quadrants 48 of the cup member, a film of oil or other suitable material intervening. A suitable quantity of oil is normally held in the bottom of the cup 49. If the magnetizing force of the current passing through the circuit 50 breaker is exerted for a sufficiently long time upon the armature 34, the sucker eventually yields, separating from the co-operating quadrants 48. The armature 34 then moves in a clockwise direction about its pivot 33, as viewed in Fig. 2, and the striking member 31 strikes 55 the underside of the tail 30 of the latch actuating member 28, and that member, in turn, strikes upon the top of the latch 25, thus releasing the roller 23 and allowing the toggle 20, 22 to collapse, whereupon the laminated bridging member moves about its pivot away from the 60 contact blocks 1 and 2, the metallic shunt contact 9 separating from its complementary contact 8 and finally the carbon 14 separating from the carbon 12 where the final arcing occurs in a manner well understood in this art. The lip 25' of the latch 25, when actuated by the member 28, serves to deliver a blow to 65

the operator's handle 17 to hasten the opening movement. The greater the current flow through the circuit breaker the greater will be this blow and the quicker the opening movement.

The sucker, as above stated, prevents instantaneous 70 response to the overload or abnormal condition. This is a desirable mode of action, because, if an abnormal electrical condition obtains for a very short interval of time only, in many cases no damage can be done.

The surfaces of the quadrants 48 and 51 are not absolutely smooth, though smooth surfaces serve well as a sucker. The surfaces of the quadrants are slightly roughened, as by sand blasting, etching, electroplating, machining, or any other suitable process, with the result that upon each resetting of the sucker the same 80 force will, at the expiration of the same length of time, separate the sucker elements, an operation which is not true of sucker elements with perfectly smooth surfaces. Thus, when perfectly smooth surfaces are employed, if the sucker is allowed to stand a number of hours, it will 85 be found that a different force will be required to separate the sucker elements in a given time than when those elements have been in contact only a relatively short period. The roughening, above referred to, obviates this variation in the constant of the sucker and 90 renders it to all intents and purposes uniform irrespective of the time interval between setting and actuation.

The greatest amount of sucker surface is active when the quadrants 51 are directly above quadrants 48. To change this amount of co-operating surface the cup 49 95 as a whole is rotated upon the stirrup 56, the sucker member 47 remaining stationary. This adjustment of surface in the sucker makes it responsive to a given applied force in shorter and shorter times as the co-operating surface is made less and less. These times of response may be calibrated, in seconds or other time units upon the stirrup 56 and the pointer carried by the handle 72 upon the cup member 49 serves as an indication when the proper amount of surface is active in the sucker, because rotating the handle 72 rotates the cup 100 49 for the purpose above described.

It is to be understood that different materials can be used for the sucker elements, as iron, brass, etc. And the cup element 49 and its quadrants 48 may be of iron, such as cast iron, while the co-operating movable sucker 110 element may be of brass.

What I claim is:

1. In controlling mechanism, the combination with a movable element, of a start delaying device comprising juxtaposed roughened surfaces, and a liquid adhering to 115 said surfaces.

2. In controlling mechanism, the combination with a movable element, of a start delaying device comprising juxtaposed sand-blasted surfaces, and a liquid adhering to 120 said surfaces.

3. In controlling mechanism, the combination with a movable element, of a start delaying device comprising a sucker, an element of said sucker having a roughened surface.

4. An uniformly acting start delaying device comprising 125 a sucker, an element of said sucker having a roughened surface.

5. An uniformly acting start delaying device comprising a sucker, an element of said sucker having a sand-blasted surface.

6. The combination with a tripping mechanism of a circuit breaker, of a sucker associated with the movable tripping member, an element of said sucker having a roughened surface.

7. In controlling mechanism, the combination with a movable element, of a sucker, and means for adjusting the extent of the juxtaposed surfaces of the sucker elements. 8. In controlling mechanism, the combination with a movable element, of a sucker, and means for adjusting said sucker, whereby it shall yield to a certain force after various intervals of time. 9. The combination with a tripping mechanism of a circuit breaker, of a sucker associated with the movable tripping member, and means for adjusting said sucker, whereby it shall yield to a certain applied force after various intervals of time. 10. A start delaying device comprising a sucker, a surface of a sucker element being roughened, and means for adjusting the extent of the juxtaposed surfaces of the sucker elements. 11. The combination with a tripping mechanism of a circuit breaker, of a sucker associated with the movable tripping member, a surface of an element of said sucker being roughened, and means for adjusting the extent of the juxtaposed surfaces of the sucker elements. 12. In controlling mechanism, the combination with a movable element, of a sucker associated therewith, the movable sucker element pivoted upon a ring member; said ring member pivoted to a connector upon an axis at right angles to the pivotal axis of said sucker element. 13. In tripping mechanism, the combination with a magnetizable member, of a start delaying device, the movable element of said start delaying device being connected with said magnetizable member, a support for the non-movable element of said start delaying device, means for adjusting said supporting member comprising stationary and movable slotted members, and a member movable in the slot of one of said members and engaging in the slot of the other. 14. In tripping mechanism, the combination with a movable magnetizable member, of a sucker, the movable sucker element connected to said magnetizable member, a support for the stationary sucker element, means for adjusting said support to adjust the position of the magnetizable member comprising stationary and movable slotted members, the slots in said members being disposed at an angle with respect to each other, and a member movable in the slot of one member and engaging in the slot of the other to effect adjustment. 15. In tripping mechanism, the combination with a magnetizable member, of a sucker, a stationary sucker element connected to said magnetizable member, and a support for the sucker cup, said sucker cup being rotatable upon said support, whereby the extent of area of juxtaposed sucker surfaces may be varied. 16. A start delaying device comprising a sucker, a sucker element consisting of a cup, a cover therefor, and a cup support held between said cover and said cup member. 17. A start delaying device comprising a sucker, a sucker element consisting of a cup member, a cover therefor, a cup support confined loosely between said cover and cup member, whereby said cup member may be rotated upon said support to adjust the extent of juxtaposed sucker surfaces. 18. A start delaying device comprising a sucker, the sucker elements having juxtaposed sector surfaces, and means for adjusting the sectors of the stationary and movable sucker elements with respect to each other. 19. The combination with a magnetizable member, of a movable sucker element connected therewith, a relatively stationary sucker element, means for adjusting the position of said magnetizable member, and means operated by said adjusting means for correspondingly adjusting the stationary sucker element. 20. The combination with a magnetizable member, of a movable sucker element connected therewith, a relatively stationary sucker element, and coöperating fixed and stationary slotted members for simultaneously adjusting the position of said magnetizable member and said stationary sucker element. 21. The combination with a magnetizable member, of a sucker element connected therewith, a relatively stationary sucker element, means for adjusting the position of said magnetizable member, and a pivotal connection between the stationary sucker element and said adjusting means, whereby the position of the stationary sucker element is adjusted simultaneously with said magnetizable member. 22. The combination with a magnetizable member, of a sucker element connected therewith, a relatively stationary sucker element comprising a cup member, means for adjusting the position of said magnetizable member, a cup supporting member, and a pivotal connection between said cup supporting member and said adjusting means. 23. The combination with a magnetizable member, of a sucker element connected therewith, a pivoted member for adjusting the position of said magnetizable member, a relatively stationary sucker element, and means connecting said stationary sucker element with said pivoted member. 24. The combination with a magnetizable member, of a sucker element connected therewith, a pivoted member for adjusting the position of said magnetizable member, a relatively stationary sucker element, and a pivotal connection between said stationary sucker element and said pivoted member. 25. The combination with relatively fixed and stationary sucker elements, of a support for a relatively stationary sucker element, and a pivoted member connected with said support for adjusting the sucker to different positions. 26. The combination with relatively movable and stationary sucker elements, of a support for said relatively stationary sucker element, a pivoted member for moving said support, and a guide for said support during movement. 27. The combination with a relatively movable sucker element, of a relatively stationary sucker element comprising a cup member, a cup support, means for moving said cup support to different positions, and a guide. 28. The combination with a relatively movable sucker element, of a relatively stationary sucker element comprising a cup member, a cup support, a pivoted member for moving said support, and a guide. 29. The combination with a relatively movable sucker element, of a relatively stationary sucker element comprising a cup member, a cup support, a pivoted member for moving said support, a magnetizable member connected with said pivoted member, and a connection between said magnetizable member and said relatively movable sucker element. 30. The combination with a sucker element comprising a cup member, of a relatively movable sucker element, a support for said cup member upon which said cup member may be moved, and an indicator for indicating the position of said cup member with respect to said movable sucker element. 31. The combination with a sucker element comprising a cup member, of a coöperating sucker element a cover for said cup member, a cup support confined loosely between said cover and cup member, and means for indicating the relative position of the sucker elements. In testimony whereof I have hereunto affixed my signature in the presence of the two subscribing witnesses.
